UNITED STATES PATENT OFFICE.

WILLIAM F. BOUCHÉ, OF LANCASTER, NEW YORK, ASSIGNOR TO GOULD COUPLER COMPANY, A CORPORATION OF NEW YORK.

MEANS FOR DRIVING DYNAMOS FROM CAR-AXLES.

1,400,793.

Specification of Letters Patent. Patented Dec. 20, 1921.

Application filed July 14, 1919. Serial No. 310,710.

To all whom it may concern:

Be it known that I, WILLIAM F. BOUCHÉ, a citizen of the United States, and a resident of Lancaster, county of Erie, and State of 5 New York, have invented certain new and useful Improvements in Means for Driving Dynamos from Car-Axes, of which the following is a specification.

My invention relates to driving means, 10 and particularly to means for directly driving a dynamo from the axle of a railway car.

An object of my invention is to simplify the dynamo drive mechanism at the same time securing all the advantages of a belt 15 drive without the disadvantage, among others, of breakage of belt.

Another object of my invention is that the driving mechanism is mounted on the truck whereas the dynamo is mounted on the car 20 body, and simple and rugged means are provided on the car axle for propelling the driving means as will be more fully explained in the following specification taken in connection with the accompanying drawings which 25 form a part of said specification, and in which—

Figure 1 is a side elevation partly in section showing the truck, driving means and dynamo.

30 Fig. 2 is an end elevation also partly in section showing the relation of the parts; and

Fig. 3 is a plan view of the arrangement but not showing the car body.

35 In the drawings, the usual car wheels 1 are provided and are mounted on axle 2. The axle 2 carries a suitable driving means 3 upon which is carried a flexible belt 4. This belt may be of any well known construction, 40 but that shown is the Morse chain drive. Parallel to the axle 2 is a jack shaft 5 carried and supported by the truck. This jack shaft is pivoted on trunnions 6 in a frame member 7, one end of which is carried by the transom 45 35 of the truck and the other end of which is carried by the end sill 36 of the truck. The shaft may be placed in position by placing the lower trunnion 6, as shown in Fig. 2, in place and moving the upper trunnion in 50 position and bolting on the plate 8 by means of the bolts 9, as shown in Fig. 3. This pivoted arrangement permits the jack shaft 5 to be adjusted with respect to the axle 2 for the principal purpose of permitting the driving belt 4 to be tightened or loosened as oc-

casion may require. The shaft 5 is adjusted and held in position by means of a flanged nut 10 which is screwed onto a member 11, which engages a bearing 12 upon the end of the shaft 5. The bearing to which the member 11 is attached is held by guides 13, which coöperate with the member 14 mounted on the truck. 60

By reason of the flanges on the nut 10 engaging with the H-member 15, the shaft 5 is moved in the proper direction by properly moving the nut 10 by any suitable means such as for instance inserting a rod in the holes 16, as will be apparent from Fig. 3. It will be noted that the adjusting means are 70 placed upon one side of the pivotal axis 6, whereas the driving gears, as will be presently explained, are mounted on the other side.

Mounted on the shaft 5 is a gear or pulley 75 which coöperates with the belt 4 driven from the car axle. The gear or pulley mounted on the shaft 5 is not visible in any of the figures of the drawing and this member may take any usual or desired form and be of the required dimensions with relation to the means on the driving axle to give the proper speed. Mounted on the shaft 5 is a bevel gear 17, which meshes with a bevel gear 18 mounted on the shaft 19. Surrounding the gears 17 and 18 is a housing 20 which is carried by the trunnions 6 and so arranged as to move around the pivotal axis with the shaft 5. The shaft 19 has bearings in the housing 20 to hold the gears 17 and 18 in proper relation to each other. The shaft 19 together with the shaft 21, which extends through an opening in the floor 38, and shaft 22 and the universal joints 23 and 24 constitute the dynamo propeller shaft for the purpose of 95 transmitting the driving power from the jack shaft 5 to the dynamo shaft 25. The universal joints 23 and 24 are connected with the shafts 19, 21 and 22 respectively in the ordinary way. Each of these universal joints 100 has a casing 26 surrounding the same and also a suitable arrangement 27 for completely inclosing the joints and for the primary purpose of excluding dust and retaining suitable lubricant. 105

By reason of the inclusion of the universal joints in the propeller shaft, it is not material that the dynamo shaft be in any particular fixed position with respect to the jack shaft. The lower universal joint is 110

connected at one end with a socket member 28 into which extends an extension 29 on the end of the shaft 21. The shaft 21 fits snugly but movably within the socket member 28 so as to provide for relative up and down movement between the shafts 19 and 21. This arrangement is necessary by reason of the fact that there is a relative vertical movement between the car body on which 10 the dynamo is carried and the truck upon which the jack shaft 5 and other driving means are carried and compensates for the movement of the car springs. The power from the shaft 22 is transmitted to the dynamo shaft 25 by gears 30 and 31. These gears are inclosed in a housing 32 which is carried by the dynamo bearing block 33. The shaft 25 drives the armature of the dynamo 34 in a well known way.

20 The housings 20 and 32 are each provided with a cap 37 covering an opening through which suitable lubricant may be admitted for the gears.

From the foregoing it will be evident that 25 with the arrangement above described, means are provided for driving the dynamo from the car axle. The driving means are pivotally connected with the truck and all the driving apparatus is carried by the truck 30 except a single pulley or gear, which is mounted on the car axle. While the dynamo propeller shaft has been shown as extending substantially vertically from the jack shaft, the invention is not limited to 35 that particular arrangement because the arrangement shown in the accompanying drawings is that of a so-called train lighting system as distinguished from a car lighting system where there is an equipment on 40 each individual car. It is apparent that suitable and simple changes could easily be made to adapt the arrangement shown to a car lighting system.

Having described my invention, what I 45 claim as new and desire to secure by Letters Patent is:

1. In a device of the character described, the combination of a car and its axle, a pivoted jack shaft parallel with said axle, said 50 shaft having a journal bearing pivoted to swing about an axis at right angles to the shaft, means on one side of the pivot for driving the jack shaft from the axle, a dynamo, a propeller shaft for driving the dynamo, and means on the jack shaft on the other side of the pivot for driving said propeller shaft.

2. In a device of the character described, the combination of an axle, a pivoted jack 60 shaft parallel with said axle, said shaft having a journal bearing pivoted to swing about an axis at right angles to the shaft, a chain belt on one side of the pivot for driving the jack shaft from the axle, a dynamo, a pro-

peller shaft for driving the dynamo, means 65 on the jack shaft on the other side of the pivot for driving said propeller shaft, a casting for said last mentioned means secured to said journal, and means for adjusting said jack shaft around said pivot. 70

3. In a device of the character described, the combination of a car and its axle, a dynamo for driving the dynamo from the axle comprising a pivoted counter shaft normally parallel to said axle and pivoted to swing 75 on an axis at right angles to the axis of said shaft, and carried by the car truck, a chain belt on one side of the pivot for driving the counter shaft from the axle, a gear on the counter shaft, on the other side of the pivot 80 a propeller shaft for the dynamo, a gear on the propeller shaft in mesh with the counter shaft gear, a housing for said gears acting also as a support for said propeller shaft, and means for adjusting said counter shaft 85 around its pivot.

4. In an arrangement of the class described the combination of a car and its axle, a jack shaft normally parallel to the axle, a bearing for the jack shaft pivoted to swing 90 about an axis at right angles to the shaft, another bearing for the jack shaft and means for moving it to adjust the position of the shaft with respect to the axle, flexible means for driving the shaft from the axle, 95 a dynamo and means for driving the dynamo from the jack shaft.

5. In an arrangement of the class described the combination of a car and its axle, a jack shaft, normally parallel to the 100 axle, a bearing for the jack shaft pivoted to swing about an axis at right angles to the shaft, another bearing for the jack shaft and means for moving it to adjust the position of the shaft with respect to the axle, 105 said bearings being supported on the car truck, flexible means for driving the shaft from the axle, a dynamo supported by the car body, and shafting with universal joints for driving the dynamo from said jack 110 shaft.

6. In an arrangement of the class described the combination of a car and its axle, a jack shaft normally parallel to the axle, a bearing for the jack shaft pivoted to 115 swing about an axis at right angles to the shaft, another bearing for the jack shaft and means for moving it to adjust the position of the shaft with respect to the axle, said means including a screw threaded member and co-operating nut member, flexible means for driving the shaft from the axle, 120 a dynamo and means for driving the dynamo from the jack shaft.

In testimony whereof, I have signed my 125 name to this specification.

WILLIAM F. BOUCHE.
